UNITED STATES PATENT OFFICE.

HENRY A. HOLT, OF WILTON, NEW HAMPSHIRE.

MACHINE FOR EDGE-SAWING LUMBER.

SPECIFICATION forming part of Letters Patent No. 536,832, dated April 2, 1895.

Application filed November 19, 1892. Renewed June 29, 1894. Serial No. 516,127. (No model.)

To all whom it may concern:

Be it known that I, HENRY A. HOLT, of Wilton, in the county of Hillsborough and State of New Hampshire, have invented certain new and useful Improvements in Machines for Edge-Sawing Lumber, of which the following is a specification.

This invention relates to machines for edge-sawing lumber, and has in view for one thing, 10 the provision of a carriage for the lumber which is so narrow as to permit the sawing of the narrowest strips.

Another object is to provide simple and conveniently operated devices for dogging the lumber.

15 A third object is to provide improved means for controlling the reversible driving mechanism by the travel of the carriage, and a fourth object is to provide means for automatically releasing the lumber from the dogs on the completion of the sawing.

To the above ends, the invention consists in certain novel combinations of parts which are recited in the appended claims.

25 The accompanying drawings illustrate a machine embodying the invention.

Figure 1 shows the machine complete, in front elevation. Fig. 2 shows the same in top plan, with the bed or table broken out at one part to disclose parts under it. Fig. 3 shows a broken longitudinal section of the machine. Fig. 3^a shows a cross-section taken on line 3^a—3^a of Fig. 3. Fig. 4 shows the head and tail-blocks of the carriage in plan, and certain adjuncts thereof, some parts being represented as broken away and others indicated by broken lines. Fig. 5 shows the head-block in rear elevation, and certain adjuncts thereof, full lines showing one adjustment of parts and broken lines another. Figs. 6 and 7 show 30 respectively a rear end elevation and a longitudinal section of the tail-block. Fig. 8 shows a top plan view of the reversible driving mechanism and the saws. Fig. 9 shows a 35 detail of said adjusting means.

The letter *a* designates the supporting frame of the machine, and *b* a horizontal bed or table on said frame. At the forward part of the table there is formed a channel *b*² extending 40 the full length of the table, and a track consisting of a single line of rails *i* is laid in the said channel, the rails being preferably dove-

tailed in cross-section. Fitted to the said track are the head and tail-blocks *g* and *h*, between which the lumber is carried. A rod 55 *f*'' is fastened at one end in the head-block *g*, and passes loosely through the tail-block *h*, and is fastened at the other end in an auxiliary block *a*'' which fits the track.

A piece of board to be sawed is placed on 60 the table *b*, between the head and tail-blocks, and is slid over said table by the action of the tail-block against it. The said tail-block is adjusted to the length of the board by sliding it along on the rod *f*'', and is clamped to said 65 rod by means of a cam-lever *h*'' (see Fig. 7) or other suitable means of convenient manipulation.

The front end of the piece of lumber is wedged under a dog *j*'' on the block *g*, and 70 the block *h* carries affixed on its upper side a dog *i*'', which is caused to penetrate the rear end of the lumber by movement of said block *h* to clamping position.

The blocks *g* and *h*, the rod *f*'', and the auxiliary block *a*'' may be said to constitute a carriage, which carriage is caused to traverse the track *i* by the following-described mechanism: A cable *l* is attached at one end to the block *a*'', and at the other end to the block *g*, 80 the latter attachment being effected by means of a cam-lever 2 which is pivoted to a lug on the block and engages an eye 3 on the cable. (See Fig. 5.) The object of this mode of connection is to secure detachability; for by 85 throwing the lever 2 upward, the tension of the cable is relaxed and its eye can be readily disengaged from the lever, whereas by turning said lever down when engaged with the eye, the cable is drawn taut and the eye is carried 90 over the lever's center so that said lever is held down. The strain of the cable is taken by the lug on the block, and not by the lever. The cable *l* passes out of the ends of the channel *b*², and oversheaves *m* which are supported in 95 bearings projecting out from the ends of the machine. From said sheaves the cable is brought inward and wound on a drum *k* and secured to the same. It will now be apparent 100 that rotation of the drum will cause movement of the carriage on the track, and by rotating said drum alternately in opposite directions, reciprocations of the carriage are produced. The drum carries a gear *n*, which

is in mesh with a pinion o affixed on a shaft p journalized in a swinging frame q off the center of the frame, and carrying a friction-wheel r . Movement of said frame shifts the said wheel r for engagement with one or the other of two driving friction-wheels s u , which determine the direction of rotation of the wheel r and consequently the drum k . The friction-wheel s is carried by the journal of a cone-pulley t , whereas the wheel u is on the journal of a gear v which meshes with a gear w on the journal of a cone-pulley x . The two cones are connected by a belt z , and the cone s is driven through any suitable connection with a source of power. It is here shown as connected by a crossed belt y with the saw-shaft c , which carries a pulley f for connection in any suitable manner with a source of power.

For varying the speed of the cones, I provide a shipper z^3 engaging the belt z , the said shipper being affixed to a sliding rod z^5 , which is engaged by a lever z^4 accessible at the front of the machine.

Connected with the pendent portion f' of the frame q , there is a rod g' which also connects with a crank e' affixed to a shaft d' carrying a segment c' in mesh with a segment b' on the lower end of a lever a' . The said lever extends upward through a slot in the table b and in easy reach of an attendant who by operating said lever can reverse the motion of the carriage at will; for it will be seen that movement of the lever is transmitted to the swinging frame q . The two extremes of the lever's movements are indicated in Fig. 3 by full and dotted lines, and the corresponding positions of co-acting parts are similarly indicated. There is an intermediate position of parts when no motion is transmitted to the

40 drum and the lever stands perpendicular, and this adjustment is caused to be automatically assumed at the end of each movement of the carriage, through the following-described means, reference being had to broken-line 45 illustration in Fig. 2:

A pair of levers v'' and d''' are pivoted on the under side of the table and extend by the lever a' on opposite sides thereof; and rods r'' and c''' are connected with said levers respectively and extend along under the table for a considerable distance to allow for the runs of the carriage. At their ends the said rods are formed with offsets g'' and b''' which project into the channel b^2 for abutment of a 50 pendent lug h^4 (see Fig. 6) on the block h , and of the block a''' respectively, the former abutting the offset g'' at the end of the forward run of the carriage, and the latter abutting the offset b''' at the end of the backward run.

55 The movement of the reach-rod r'' or c''' produced by such abutment shifts the lever with which it connects and causes said lever to act against the lever a' and move the latter to vertical position, the said lever a' , by 60 its movement which sets the carriage in motion, having come to bear against the shifting lever.

In conjunction with the rod r'' , there are arranged devices for automatically disengaging the dog j'' of the head-block from the board when the carriage has reached the limit of its forward run, the said devices being of the following description, with reference more particularly to Figs. 2, 4, and 5: The said dog j'' is pivoted to the block g and pressed forward for engagement with the board by a spring y'' , and normally locked in the forward position by engagement of the catch of a pivoted pawl k'' on the block with a shouldered collar k''' on the pivot of the dog, the said pawl being also actuated by the spring y'' . The said pawl lies longitudinally of the block g , and has a beveled rear end, as clearly shown in Fig. 5. A block l'' is fitted to the track i and carries on one side a spring-latch m'' for engagement with a notch n'' in the head-block g . The said block l'' is formed with upstanding ears through which a bolt p'' is fitted to slide, the said bolt being pressed back by a spring o'' surrounding it beyond the block l'' and bearing at one end against the latter and at the opposite end against the head of the bolt. The forward end of said bolt is beveled for co-action with the bevel of the pawl k'' . A holding-rod u'' extends along under the table inwardly beyond the rod r'' , and said rod u'' has an outwardly bent end formed to embrace the bolt p'' to which it is fastened. The rod u'' extends between clamping jaws t'' and t''' one of which is movable and the other fixed, and the movable jaw t'' is beveled on the outer side for engagement of the back edge of the rod r'' . The latter is formed with an oblique edge s'' at the base of the offset q'' , which oblique edge is adapted to be acted upon by the lug h^4 of tail-block h .

In the advance of the carriage, its block g runs behind the spring-latch m'' , and the latter snaps into the notch n'' . Then the block l'' is carried forward with the block g and also with the bolt p'' and rod u'' , until the lug h^4 by acting on the oblique edge s'' presses the jaw t'' against the rod u'' , when the latter is locked and hence holds the bolt p'' from further movement, so that the continued advance of the head-block carries the beveled end of the pawl k'' upon the beveled end of the bolt, and this effects displacement of said pawl and release of the dog j'' .

In the return movement of the carriage, the head-block carries the block l'' with it until the latter is restored to its initial position. It will be understood that in this return movement the blocks l'' and g move before the rod u'' and bolt p'' , so that the pawl k'' is taken free of the said bolt and is restored to engagement with the collar k''' by the spring y'' , which also restores the dog j'' to position for engagement with the next piece of lumber.

A lug z'' under the table stands in the path of the latch m'' on the return movement, and when said latch encounters this lug it is moved out of engagement with the notch n'' (see Fig. 2), and the head-block then leaves the block l'' .

The purpose of the construction above described, which provides a movable releasing device is to allow for varying lengths of boards, for it will be apparent that the extent of the 5 advance of the carriage depends on the length of the board, as it is the tail-block which throws the machine out of action, and this tail-block is adjusted to the length of board. Therefore the release of the sawed boards must depend 10 on their length, so that their rear ends will always stop at the same place. Sufficient range of movement is provided for in the releasing devices to accommodate any length of board, and the sliding block l'' is always brought 15 back where it will be acted upon by the advancing head-block. The lug z'' is a fixture which determines the position in which the block l'' shall be left.

The saw-shaft or arbor c hereinbefore mentioned extends under the track i , and is here shown as equipped with two saws d and e , the saw d being fixed to the shaft in line with the inner side of the channel b^2 ; whereas the saw e is adjustable on the shaft, being splined 20 thereto. The saw e is adjusted through the following means: Said saw has an extended hub p' formed with an encircling groove q' , which is engaged by a fork r' whose shank s' is adjustably fastened in an arm t' (see Figs. 25 3 and 9) having a long boss t^2 which is pivoted on screws u' entered through ears v' of a dovetailed slide w' which fits a groove of corresponding form in a bar x' fastened to the frame of the machine and extending parallel 30 with the saw-arbor. Said bar x' has a rack y' on its under side engaged by a pinion z' on one end of a shaft a'' whose opposite end carries a bevel-pinion b'' (see Fig. 2) meshing with a bevel-gear c'' on a cross-shaft d'' carrying a hand-wheel e'' on its outer end. It 35 will be seen that by turning said hand-wheel the slide w' is moved, and consequently the saw e . The position of said saw determines the width of the strip cut from the board passing 40 through, and the saw is adjusted by a gage o' extending over it.

On the upper side of the table b , somewhat back from the channel b^2 , there is a guide-board h' which extends parallel with the edge 45 of the table at said channel, and is adjustable to vary the distance between it and that edge, its adjustment being effected through the following-described means: Racks i' are fastened to the rear side of the board, and they are engaged by pinions j' on a shaft k' , which also carries a worm-wheel l' engaged by a worm on an inclined shaft m' supported in suitable 55 bearings erected on the table and carrying a hand-wheel n' . It will be seen that by turning said hand-wheel the guide-board will be moved forward or back according to which way the wheel is turned. The guide-board determines the width of a strip to be cut from one side of a board by the saw d , and said 60 guide-board is adjusted by a gage o'' extending above it (see Fig. 3 a), the guide-board having an index-finger h^x pointing toward the

gage. This gage o'' and the gage o' are shown as marked on the same bar, which extends entirely across the machine.

The general operation of the machine may be stated as follows:—The carriage being ready for a forward run, as shown in Figs. 1 and 2, the board to be operated upon is brought onto the table, and its forward end wedged under the dog j'' of block g . The board is let down to rest flat on the table, covering the channel b^2 , and the block h is moved along the rod f'' , and its dog caused to penetrate the rear end of the board. The said 70 block h is then locked to the rod f'' by means of the cam-lever h'' . The attendant shifts the lever a' , so as to start the cable, and the carriage advances, taking the board onto the saw or saws. The tail-block moves far enough 75 past the saws to give ample freedom for removing the sawed board. As the tail-block reaches the end of its movement, the automatic release of the dog j'' takes place in the manner before explained, simultaneously 80 with the stoppage of the carriage's advance. The attendant now moves the lever a' to start the cable in the reverse direction to that in which it before moved, and the carriage is run back, the releasing-block l'' being brought 85 back to normal position in the manner before explained. To prevent a strip which may be left on the outer side of the saw d from being carried back, a spring-catch w'' is provided to engage it on the under side. (See Fig. 1.) 90 The backward run of the carriage is stopped by the auxiliary block a''' coming against the offset b''' and shifting the lever a' , as has been before explained.

When a single strip is cut from a board, the 95 guide-board h' is not used, but the board to be sawed is placed with its inner edge parallel with the inner edge of the channel b^2 and overlapping the same only enough to have the edge of the board trimmed off. The saw e 100 having been adjusted to the width of strip desired saws off the strip while the saw d trims the edge.

When two strips are to be cut from a board, the guide-board h' is adjusted the distance 105 from the edge of the channel b^2 corresponding with the width of strip desired, and the board to be sawed is placed on the table with its inner edge (which has been previously 110 trimmed) against the said guide-board. Then 120 when the board is run through, one strip is sawed off by the saw d between the latter and the guide-board, and another strip is sawed off by the saw e between the latter and the saw d . Of course it will be apparent that any 125 number of saws might be used.

For the purpose of pushing the piece removed between the saw d and guide h' out beyond the saws, I fasten a yoke-shaped piece e''' to the tail-block h , the shape of said piece 130 allowing it to pass over the saw d and continue in engagement with the rear end of the board.

It is to be particularly noted that the car-

riage is so narrow that it can pass between the saws when they are very close together, and hence strips as narrow as ever required can be produced.

5 I claim—

1. In a machine for edge-sawing lumber, the combination of a horizontal table on which the lumber slides, the said table having a narrow longitudinal channel, a track on the base 10 of said channel; head and tail blocks fitting the track and each having a dog for engagement with the lumber; and a driving cable connected with the two blocks, the tail block being adjustable.
- 15 2. In a machine for edge-sawing lumber, the combination of a horizontal table on which the lumber slides, the said table having a narrow longitudinal channel; a track on the base 20 of said channel; head and tail blocks fitting the track and each having a dog for engagement with the lumber; a rod extending between the two blocks and rigidly connected with the head-block while the tail-block may 25 slide on the rod and is equipped with means for locking it at different positions; and a driving cable connected with the rod.
3. In a machine for edge-sawing lumber, the combination of a horizontal table on which the lumber slides, the said table having a narrow 30 longitudinal channel; a track on the base of said channel; head and tail blocks fitting the track and each having a dog for engagement with the lumber; a rod fastened at one end to the head-block and extending loosely 35 through the tail-block which is provided with clamping devices; an auxiliary block fastened to the rod; a cable connected with the head-block and the said auxiliary block; reversible driving mechanism connected with the cable; 40 and reversing means arranged to be tripped by the tail-block and the auxiliary block.
4. A machine for edge-sawing lumber, comprising in its construction a reciprocating carriage having a fixed dog i'' at one end, a pivoted dog j'' at the other end and having a heel engaged by a pivoted pawl k'' , and means for positively moving the said pawl to cause it to engage and disengage the heel of the dog j'' , substantially as described.
- 50 5. A machine for edge-sawing lumber comprising in its construction a reciprocating carriage composed of block h having dog i'' and block g having pivoted dog j'' , latch pawl k'' and notch n'' , the block l'' having spring latch 55 m'' , a spring bolt p'' carried by block l'' and having an inclined end to act on pawl k'' , and means for disengaging the latch m'' from the notch n'' , substantially as described.
6. A machine for edge-sawing lumber, com-

prising in its construction edging saws, a reciprocating carriage embracing a head-block, a tail-block, and a connecting rod, the tail-block being provided with a fixed dog and with means for adjustably securing it to the said rod, and the head-block being provided 60 with a pivoted dog j'' having a heel engaged by a pivoted pawl k'' , and means for positively moving said pawl to cause it to engage and disengage the heel of the dog j'' , substantially as described.

7. A machine for edge-sawing lumber comprising in its construction edging saws, a carriage embracing a head-block and a tail-block adjustably connected together and provided with dogs for holding the lumber, means for reciprocating the carriage, a lever a' for controlling the operation of the said reciprocating mechanism, the sliding rods $r'' c'''$, the levers $v'' d'''$ connected to said rods and extending on opposite sides of the lever a' , and projections on the carriage adapted to engage with and move the sliding rods, whereby the levers $v'' d'''$ may be caused to move the lever a' to stop the carriage at each end of its travel.

8. A machine for edge-sawing lumber comprising in its construction edging saws, a sliding carriage, a drum, flexible connections between the carriage and drum, means including a rocking frame for reversing the direction of rotation of the drum, the lever a' for controlling the operation of the reversing mechanism, the sliding rods $r'' c'''$, the levers $v'' d'''$ connected to said rods and extending on opposite sides of the lever a' , and projections on the carriage adapted to engage with and move the sliding rods, whereby the levers $v'' d'''$ may be caused to move the lever a' to stop the carriage at each end of its travel.

9. In a machine for edge-sawing lumber, the combination with a reciprocating carriage 90 having a head-block with a movable dog for engaging the lumber and a detent for locking and releasing the said dog, and an adjustable tail-block; of a slide in front of the carriage, a latch to connect it therewith, a trip loosely 95 mounted on the slide and arranged to coact with the dog-engaging detent, a holding rod fastened to said trip, and means actuated by the tail-block of the carriage for locking said rod.

In testimony whereof I have signed my name to this specification, in the presence of two subscribing witnesses, this 5th day of November, A. D. 1892.

HENRY A. HOLT.
